(57) **CLAIM**

The ornamental design for a medical injector pen, as shown and described.

DESCRIPTION

FIG. 1 is a perspective view of a medical injector pen with the cap removed, in accordance with the present invention, in which the color of the pen body, the color of the dosage knob, and the color of the actuator button all form part of the design. The color of the pen body is Pantone 53 8C, the color of the dosage knob is Pantone 2766C, and the color of the actuator button is Pantone 272C;

FIG. 2 is a front elevational view thereof, with the cap removed;

FIG. 3 is a left side elevational view thereof, with the cap removed;

FIG. 4 is a right side elevational view thereof, with the cap removed;

FIG. 5 is a rear elevational view thereof, with the cap removed;

FIG. 6 is a top plan view thereof, with the cap removed; and, FIG. 7 is a bottom plan view thereof, with the cap removed.
